United States Patent

Des. 236,396
Patented Aug. 26, 1975

236,396

HOSE HOLDER

Phillip H. Huyssen, 116 Baber St.,
Hot Springs, Ark. 71901

Filed Sept. 19, 1973, Ser. No. 398,680

Term of patent 14 years

Int. Cl. D6—99

U.S. Cl. D6—85

FIG. 1 is a perspective view of a hose holder embodying my new invention;

FIG. 2 is a side elevational view;

FIG. 3 is a front elevational view;

FIG. 4 is a rear elevational view; and

FIG. 5 is a top plan view.

The bottom handle in FIG. 5 has been shown in an alternate position.

I claim:

The ornamental design for a hose holder, as shown and described.
